Robert B. De Vay, 69—40 108th St., Forest Hills 75, N.Y.

Filed Sept. 30, 1964, Ser. No. 81,952

Term of patent 3½ years

(Cl. D45—17)

FIG. 1 is a front plan view of a charm or similar article showing my new design;

FIG. 2 is a side elevational view thereof,

FIG. 3 is a rear view thereof,

FIG. 4 is a transverse sectional view taken on line 4—4 of FIG. 1, and

FIG. 5 is a disassembled perspective view thereof.

The essential features of the design reside in the full line portions on the drawing.

I claim:

The ornamental design for a charm or similar article, substantially as shown and described.
